GAS BURNER

Herbert R. Palmer, Cleveland, Ohio

Application March 15, 1934, Serial No. 715,732

6 Claims. (Cl. 158—117)

My invention relates generally to gas burners and more particularly to gas burners of the double burner construction, including a mixing tube in which the gas is mixed with a certain amount of primary air before issuing from the flame openings or ports.

The principal object of the invention is to provide means for checking the flow of air and gas mixture at a point adjacent to but slightly below the flame openings.

Other objects and advantages will become apparent from the following description taken in connection with the accompanying drawing which illustrates a preferred embodiment of the invention, and in which:

Figure 1 is a plan view of my improved burner;

Figure 2 is a longitudinal sectional view taken on the line 2—2 of Figure 1;

Figure 3 is a plan view of the burner partly in section, the section being taken on line 3—3 of Figure 2.

Referring more particularly to the drawing B denotes the burner as a whole, comprising the gas and air mixing tube 1, adapted to be supplied with gas through the customary gas cock opening 2, from a manifold, not shown. Primary air is drawn into the mixing tube through side air openings 2' by the inflowing gas. A collar 3 is preferably provided for regulating the in-flow of air.

The inner end of the tube 1 terminates in an enlarged bowl-shaped burner head 4, having an upstanding outer flange or wall 5 and an inner flange or wall 6 concentrically disposed with respect to and spaced from the outer wall 5. While the outer wall 5 of the burner as shown, is fluted to increase the flame area, this wall may be round. The annular space between the walls 5 and 6 constitutes a distributing chamber 7 for the inner and outer flame outlets or ports 8 and 9 respectively. Secondary air for the port 8 is drawn in through a centrally disposed passage 10 extending vertically through the burner head 4, and within the confines of inner wall 6.

The distributing chamber 7 is partially closed at its upper end by a plate 11, which is supported in slightly spaced relation to and directly above the top horizontal edges of the walls 5 and 6 by means of threaded bolts 16, fixedly mounted in bosses 13 formed in the bowl shaped burner head portion 4. Plate 11 is provided with a round centrally disposed aperture or opening 14 which coincides in size and registers with the opening 10, and the outer edge of the plate is corrugated or otherwise shaped to correspond to the con-

tour of the outer wall 5. The unobstructed annular inner and outer openings or ports 8 and 9 defined by the top edges of the walls 5 and 6 and the bottom face of the plate 11 are adapted to support annular flames when gas is supplied to the burner. The outer peripheral edge of the plate 11 extends beyond or overhangs the wall 5 and port 9, and thus serves as a guard to prevent food and other drippings from clogging the flame openings. Likewise the inner periphery of plate 11 is slightly beveled as at 12, so that this beveled portion will slightly overhang the inner face of wall 6. A baffle member 13 located in the air opening or passage 10, and preferably supported from plate 11 by means of arms 14', 15 prevents a too free flow of air to the gas ports or flame openings.

An annular baffle plate 15, positioned within the top of distributing chamber 7, slightly below the top edges of walls 5 and 6, is adjustably supported on the bolts 16 previously referred to. The inner peripheral edge of annular plate 15 seats snugly against the outer face of inner wall 6, and preferably forms a tight seal against the passage of gas between the inner wall and the plate, and the outer edge of plate 15 is spaced from the inner face of outer wall 5 to provide the annular vertically disposed gas passage 16'. In order to counteract the tendency of the swiftly flowing stream of gas to be discharged past that portion of the opening or passage 16' adjacent the mixing tube, I have found it desirable to increase the width of the passage at this point as indicated at 17. Sufficient gas flows through this crescent shaped enlargement to insure a uniform supply of gas being delivered to the ports 8 and 9 throughout their entire circumferential area.

It will be noted that the mixing tube 1 is entirely unobstructed, as distinguished from the Venturi type generally employed. The elimination of the venturi is made possible by the use of the plate 15, and the latter also permits of a full flow or unchecked head of combustible mixture being delivered to the burner head in close proximity to ports 8 and 9, which of course is most desirable. A tube of much larger size than customarily used can thus be employed and the burner can readily be turned to a very low simmering position without danger of back firing as the flame is sufficiently removed from the annular passage 16'.

The action of the burner is as follows: The gas mixture from tube 1 passes through annular passage 16' and thence out through annular port 9, to support a ring like outer flame. A portion 55

of the gas will flow inwardly over the top of plate 15 to and through the inner annular port 8 to support a second and smaller inner annular flame, the secondary air for which is drawn 5 through opening 10.

The baffle plate 15 will be adjusted to its proper height by the manufacturer, but if required further adjustment can be made by the user, nuts 20, 20' being provided for this purpose. Top 10 plate 11 can also be readily raised and lowered by screwing up or unscrewing a nut 18. A split washer 19 is preferably interposed between the plate 11 and the nut 20' so that adjustment of the top plate can be made without interfering 15 with the fixed adjustment of the baffle plate.

Having thus described my invention:

1. A gas burner comprising a bowl shaped body having an open top, an outer wall and a substantially cylindrical inner wall axially aligned 20 with and spaced from said outer wall to provide a substantially ring shaped mixing chamber, an axially perforated plate adjustably mounted slightly above said open top providing substantially concentric inner and outer circumferential 25 outlet passages from said chamber to the open atmosphere, means for mounting said plate, and a ring shaped, solid, horizontally arranged baffle member within said mixing chamber for subdividing same and connecting the subdivisions of 30 said chamber by a narrow substantially ring shaped passage adjacent to the outer wall of said chamber for directing the gas toward said outer outlet passage, said means for supporting said plate also supporting said baffle member in slightly spaced relation from the open top of 35 said mixing chamber.

2. A gas burner comprising a body including a burner manifold and provided with an open top and a substantially ring shaped mixing chamber, a plate fitting the open top of said chamber mounted slightly above said open top for providing substantially concentric outlet passages from said chamber to the open atmosphere, and a ring shaped baffle member within said mixing 45 chamber shaped to restrict the passage through said chamber to a narrow substantially ring shaped passage adjacent to the outer wall of said chamber, said passage being of greater width at the burner portion adjacent said manifold to 50 insure uniform supply of gas to the concentric passages throughout their entire circumferential area.

3. A gas burner comprising a body having an open top and a substantially ring shaped mixing 55 chamber, the inner cylindrical wall of which forms an open ended passage and the outer wall of which is fluted to provide an outlet opening of varying area at the top of said chamber, a flat, centrally perforated plate shaped to fit the

open top of said chamber mounted slightly above the open top of said body to provide substantially concentric outlet passages from said chamber to the open atmosphere, means within said open ended passage to partly obstruct a flow of air 5 through said open ended passage, and a ring shaped baffle member within said chamber shaped to subdivide said chamber into upper and lower compartments communicating with each other through a restricted narrow ring shaped opening 10 adjacent to the outer wall of said chamber.

4. A gas burner comprising a bowl shaped body having an open top, a fluted outer wall and a cylindrical inner wall axially aligned with and spaced from said outer wall to provide a 15 substantially ring-shaped mixing chamber enclosing an axial passage through said body, a flat, axially perforated plate having the irregular configuration of said chamber mounted slightly above the open top thereof in alignment with the inner 20 and outer walls to provide two substantially concentric narrow outlet passages adjacent to the inner and outer walls of said chamber, and a ring shaped baffle member within said chamber shaped to form a restricted narrow ring shaped 25 passage adjacent to the outer wall of said chamber.

5. A gas burner comprising a manifold of unrestricted cross section, a bowl shaped body at one end of said manifold having an open top 30 and a substantially ring shaped mixing chamber, a flat, axially perforated plate having approximately the configuration of said mixing chamber mounted slightly above the open top of said body to provide substantially concentric narrow inner 35 and outer outlet passages for the gas and air mixture discharged from said mixing chamber, and a ring shaped plate within said chamber and contacting with the inner wall thereof and slightly spaced from the outer wall of said chamber 40 and adapted to subdivide said chamber into upper and lower compartments communicating with each other through a restricted ring shaped opening.

6. A gas burner comprising a body having an 45 open top and a substantially ring shaped distributing chamber the inner wall of which forms an open ended passage, a plate fitting the open top of said chamber mounted slightly above said open top to provide an outlet passage from said 50 chamber to the open atmosphere, a plurality of supporting posts for said plate extended through said chamber and a baffle plate within said chamber adjustably mounted upon said posts and slightly spaced from the open top of said chamber, and a baffle member adjustably mounted in 55 said passage.
